UNITED STATES PATENT OFFICE.

ZEAN E. MORTON, OF SHAWNEE, OKLAHOMA.

SIGNALING DEVICE.

1,368,824.

Specification of Letters Patent. Patented Feb. 15, 1921.

Application filed May 23, 1919. Serial No. 299,374.

To all whom it may concern:

Be it known that I, ZEAN E. MORTON, a citizen of the United States, residing at Shawnee, in the county of Pottawatomie and 5 State of Oklahoma, have invented new and useful Improvements in Signaling Devices, of which the following is a specification.

The present invention has reference to signaling apparatus and is designed particularly for use by railroad men to enable them to signal by means of a lantern, torpedoes or fusees as the exigencies of a case may require.

The improvement contemplates the employment of an ordinary railway lantern employed for signaling purposes having associated therewith receptacles for fusees or flares, torpedoes and matches for lighting the fusees or flares, all of the receptacles being 15 provided with suitable closures whereby the contents thereof will be protected from weather conditions as well as from contact by unauthorized persons, but at the same time being readily accessible for use by the 20 operator, and the arrangement of the receptacles being such as to in nowise interfere with the display of the light of the lantern.

The foregoing objects, and others which 25 will appear as the nature of the invention is better understood may be accomplished by a construction, combination and operative arrangement of parts such as is illustrated by the accompanying drawings.

30 In the drawings:

Figure 1 is a perspective view of my improved signaling apparatus.

Fig. 2 is an end elevation looking toward the match receptacle, parts being broken 40 away and parts being in section.

Fig. 3 is a horizontal sectional view approximately on the line 3—3 of Fig. 1.

Fig. 4 is a sectional view approximately on the line 4—4 of Fig. 2.

Fig. 5 is a horizontal sectional view approximately on the line 5—5 of Fig. 1, the door of the torpedo receptacle being shown in its open position.

The lantern construction of my improvement includes a preferably cylindrical base 10 closed at both the top and bottom thereof but having its side provided with an elongated opening 11 normally closed by a door 12. The door, of course, conforms to 55 the peripheral shape of the base and has one of its ends provided with a substan-

tially U-shaped extension 13, the connecting element for the arms whereof being approximately centrally formed with an outstanding or offset portion 14. This offset is 60 engaged by a spring tongue 15 formed centrally on one end of a plate 16 which is secured to the base 10. The tongue is preferably formed by slitting the plate longitudinally, and the plate, to the opposite 65 sides of the tongue is rounded upon itself as at 17 to receive the portions of the U-shaped member to the opposite sides of the offset 14. The opposite or free end of the door 12 is provided with a finger piece 18 whereby 70 the said door may be swung to open or closed position. The hinge connection between the door and the base is such as to effectively hold the door closed or likewise effectively hold the door in open position. 75 The base 10 provides a receptacle for the torpedoes 19. The closed top 20 of the base or receptacle 10 is preferably provided with a central round opening which receives therethrough a cup-shaped member 21, the 80 latter being flanged at its outer portion as at 22 to overlie the top of the base, and this flange 22 is peripherally provided with an upstanding collar 24 which is perforated and which has secured to the outer edge 85 thereof the vertical strands of wire of the protector frame 25 for the globe or chimney 26 of the lamp. The cup-shaped member 21 provides a receptacle for the oil bowl 27 that is provided with the usual burner having the 90 usual means for regulating the wick, the last mentioned element passing through a suitable notch in the upper edge of the collar 24. The collar 24 is provided with an inturned annular flange or ring 28 on 95 which the shade or globe rests. The shade or globe is secured on the device by the usual hinged cap member 29 which is latched to the upper horizontal ring member 30 of the frame in the usual manner. The bottom of the base member or receptacle 10, indicated for distinction by the numeral 31 is elevated above the lower edge of the said receptacle, and is preferably centrally provided with an opening 32 to permit air entering the said receptacle and to circulate around the cup-shaped member 21 and the torpedoes in the receptacle. 105

The top of the receptacle 10 is provided with any desired number of outstanding 110 plate-like members 33, which are preferably arranged radially with respect to the recep-

tacle. These plate-like members 33 provide the base portions for the tubes 34 in which the fusees or flares 35 are received. The base plates 33 are each provided with an opening 36 therethrough, and through these openings pass the stems 37 of the fusees or flares. The tubes 34 are connected to one of the horizontal ring members 38 of the frame 25 through the medium of yoke members 39, the latter being soldered or otherwise secured to the tubes which they surround, and the ends of the yokes are wrapped around the ring member 38 and may be likewise soldered thereto. Also the inner sides of the tubes may be soldered to the ring 38. Each of the tubes is provided with a somewhat elongated cap member 40 which is designed to close the said tube, and each of the cap members is supported on the tube by a flexible element such as a small chain 41. By this arrangement it will be noted that the fusees or flares are fully protected. The tubes are of a length less than that of the fusees or flares, so that the upper or outer ends of the said fusees or flares project a suitable distance beyond the open outer ends of the tubes. Such projecting ends of the fusees or flares are, however, fully protected by the cap members 40 when the latter are arranged over the tubes. The cap members are of a length to permit fusees or flares of varying lengths being received in the tubes, and by providing the flexible connections between the tubes and caps danger of loss or misplacement of the caps is thus obviated.

In the drawings four fusee receiving tubes are illustrated, but, of course, it is obvious that more may be employed if desired. Between the oppositely disposed pairs of tubes is arranged the bail-shaped handle 42 for the lantern, the latter having its ends connected to the frame 25 and having its handle portion in the nature of a coil spring 43.

Secured to the top of the receptacle 10, to the collar 24, and if desired to the inner or confronting sides of two of the tubes 34 is an angularly disposed cylindrical receptacle 44 for matches. The match receptacle 44 is arranged at an upward inclination and is normally closed by a tubular cap 45 which is suspended from a flexible element in the nature of a small chain 46 that is connected

to one of the tubes 34. In this manner the contents of the match receptacle are fully protected from the elements.

It is believed that the advantages in providing effective protectors for the fusees, torpedoes and matches wherein such articles may be readily accessible for immediate use, and that the arrangement of the receptacles for such devices so that the same will in no manner interfere with the light from the lantern, and wherein the bowl of the lantern may be readily removed for filling, the globe thereof removed for cleaning will be fully appreciated by those skilled in the art to which this invention appertains, so that a detailed description thereof or a further description of the invention will not be necessary.

It should be stated that the grip portion 43 of the handle is formed by centrally coiling the wire member from which the handle is formed. This coiled portion stiffens the handle as well as affording a better grip for the holder.

Having thus described the invention, what is claimed as new, is:—

In a signaling apparatus, a receptacle for torpedoes having an elevated bottom provided with an opening, an opening in the side thereof, a spring influenced hinged door normally closing said last mentioned opening, a cup member entering from the center of the closed top of the receptacle having an outer collar and a skeleton frame secured to the collar, said cup member designed to receive the bowl of a lamp and the frame serving as a protector for the globe of the lamp, a handle secured to the frame, tubes arranged to the opposite sides of the handle and having apertures in the closed bottoms thereof, said tubes designed to receive fusees therein and the stems of the fusees designed to pass through the apertures in the closed bottom of the tubes, tubular cap members for closing the tubes, flexible elements connecting the cap members with the respective tubes, an inclined receptacle secured to the top of the torpedo receptacle arranged between two of the tubes and connected to said torpedo receptacle, and a cap for said last mentioned receptacle.

In testimony whereof I affix my signature. 105
ZEAN E. MORTON.
